UNITED STATES PATENT OFFICE

CHRISTO STOYANOFF, OF TORONTO, ONTARIO, CANADA

DESIGN FOR A SOFT-DRINK-DISPENSER BASE

Application filed March 18, 1930. Serial No. 34,960. Term of patent 7 years.

To all whom it may concern:

Be it known that I, CHRISTO STOYANOFF, a subject of the King of Great Britain, and a resident of the city of Toronto, in the county of York, in the Province of Ontario, Canada, have invented a new, original, and ornamental Design for a Soft-Drink-Dispenser Base, of which the following is a specification, reference being had to the accompanying drawing, forming part thereof.

Fig. 1 is a front elevation of the soft drink dispenser base showing my new design.

Fig. 2 is a plan view.

I claim:

The ornamental design for a soft drink dispenser base as shown.

CHRISTO STOYANOFF.
